L. VON DABROWSKI

TRAP AND DRAIN

Filed Feb. 27, 1924

Inventor:
Lothar von Dabrowski,
By Fisher, Fowle, Clark & Doan
Atty's.

UNITED STATES PATENT OFFICE.

LOTHAR VON DABROWSKI, OF CHICAGO, ILLINOIS.

TRAP AND DRAIN.

Application filed February 27, 1924. Serial No. 695,409.

To all whom it may concern:

Be it known that I, LOTHAR VON DABROWSKI, a citizen of the United States, and a resident of Chicago, county of Cook, and 5 State of Illinois, have invented certain new and useful Improvements in Traps and Drains, of which the following is a specification.

My invention has reference more particularly to a combined trap and drain of the 10 type used in refrigerator cars.

The cooling of refrigerator cars is effected by the use of ice and salt, and it is customary to provide trapped outlets at suitable 15 points leading through the floor of the car, to drain off the water resulting from the melting of the ice. Inasmuch as the outlet pipes vary in length according to the construction of the car, the type of drains 20 now in use, which require a special construction of the outlet or drain pipe, are objectionable on account of the expense and also because such traps and pipes have to be specially made for each installation. With

25 my invention, however, this objection is avoided, as my construction does not require a special form of pipe but uses an ordinary pipe which is merely cut to length and then threaded or drilled for rivets at the ends.

30 The principal objects of my invention are to facilitate the equipping of refrigerator cars with trap and drain pipes; to avoid the necessity of special patterns to make the traps and drain pipes; to construct the device so that a plain length of pipe may be 35 employed by merely cutting the pipe to the required length and threading or drilling rivet holes at the ends; to provide an improved arrangement for mounting a trap 40 cover and a spout on the ends of the pipe; to improve the connection of the pipe with the bowl; and in general, to provide a simple, inexpensive and easily constructed drain and trap structure for refrigerator cars.

45 On the drawings:

Fig. 1 is a sectional view of my improved drain and trap, and a fragmentary portion of a refrigerator car to which it is applied;

Fig. 2 a sectional view of a modified form 50 of my drain and trap;

Fig. 3 a sectional view on the line 3—3 of Fig. 2;

Fig. 4 a vertical sectional view of a modified form of spout connection;

Fig. 5 a sectional view on the line 5—5 of 55 Fig. 1; and

Fig. 6 a sectional view showing the bowl and pipe before assembling.

Referring to the drawings, the reference numerals 1 and 2 indicate respectively the 60 inner and outer sheeting of an insulated wall of a refrigerator car, the reference numeral 3 indicating heat insulating material which is interposed between the inner and outer sheeting. A bowl-shaped member 65 4, preferably of drawn metal, is set into the bottom wall or floor of the car as shown, said bowl being provided with an annular flange 5 which is mortised into the inner sheeting 1 as shown, and secured in place 70 to a lining 7 by the rivets 6. The lining 7 of the car extends over the flange 5 and has the inner edge turned down as indicated at 8 to drain into the bowl.

The bowl 4 is formed with an opening in 75 the bottom surrounded by an upturned flange 9, and a drain pipe 10 projects up through the outer sheeting 2 and through the opening in the bottom of the bowl 4 as shown, said opening being of such size that 80 the pipe 10 has a driving fit with the flange 9, whereby the pipe is securely held in place. The pipe may also be additionally secured in place by being spot-welded in two or three 85 places at the top of flange 9.

In previous structures it has been customary to turn the flange 9 downwardly and this forms a crevice between the pipe and the bowl 4 in which sediment collects, particularly salt, which is carried off with the 90 water, and this accumulation of sediment tends to rust or eat away the adjoining metal as the same can not be easily removed. With my construction the turning up of the flange 9 forms a rounded corner at the junction of said flange with the body of the bowl 4, and prevents any such accumulation of sediment as the same cannot be easily removed. Moreover, I prefer to galvanize the 95 parts after they are assembled, and this 100

serves to fill in the offset or shoulder at the top of the flange 9 and also unites the pipe and bowl more securely.

A collar 11 is secured to the upper end 5 of the pipe 10, and has a number of lugs 12 arranged at intervals therearound and projecting up above the upper end of the pipe 10 to support a cap 13, and afford outlets 14 between the lugs 12 through which the 10 water overflows from the bowl 4 into the pipe 10. This cap 13 has an annular flange 15 extending downwardly below the openings 14 so that the level of the water in the bowl 4 is above the lower edge of the flange 15 and forms a water seal for the drainage outlet. This cap 13 is preferably hinged so that it may be turned back away from the top of the pipe 10, and to this end said cover is formed at one side with a hinge extension 20 16 embracing a laterally extending hinge lug 17 of the collar 11 to which the cover is pivoted by a pin 18, which is preferably in the form of a cotter pin.

The collar 11 may be secured on the pipe 25 10 in any convenient manner, as for example, by an ordinary threaded connection as indicated at 19 in Fig. 1, or by rivets placed at intervals around the collar 11 as indicated at 20 in Fig. 2.

For attaching a spout to the lower end of the pipe 10, a collar is likewise secured onto the lower end of the pipe by a threaded connection as indicated at 21 in Fig. 1, or by rivets as indicated at 22 in Figs. 2 and 4. 35 This spout, which is preferably of sheet metal, may be hinged directly to the collar as shown in Figs. 1 and 2, or may be hinged to the lower end of a downwardly extending section which is fixed onto the collar as 40 shown in Fig. 4. When this spout is hinged onto the collar, the latter is formed as shown at 23, with a pair of hinge lugs 24 at one side between which the upper end of the hinge strap 25 on the spout is pivoted on the 45 pin 26, which is preferably in the form of a cotter pin. The spout in such case is formed with a depending section 27 with an inclined section 28 secured to the lower end, and the upper end of the section 27 has a 50 rolled edge 29 which is held by the weight of the laterally extending section 28 against a flange 30 on the collar 23.

In the spout construction shown in Fig. 4, the laterally extending spout section 31 is 55 hinged at 32 to the upright spout section 33, and the latter has the upper end expanded to form a shoulder 34 which fits against an annular flange 35 on the collar 36, and the upper edge of the spout section 33 is turned 60 over the flange 35 as indicated at 37 to lock the spout onto the collar.

While I have shown and described my invention in a preferred form, I am aware that various changes and modifications may be 65 made without departing from the principles

of my invention, the scope of which is to be determined by the appended claims.

I claim as my invention:

1. In a refrigerator drain, the combination of a bowl having a central bottom opening with an upturned flange, a drain pipe extending upwardly through the bottom of the bowl and anchored to the flange, a cap having an annular flange extending downwardly in the bowl around and spaced from the upper end of the pipe, and an annular collar secured around the upper end of the pipe with its lower edge spaced from the bottom of the bowl and having the cap hinged thereto, said collar being provided with spaced lugs at 70 its upper end with intermediate openings for holding the cap at an elevation above the upper end of the pipe to afford a circulation space between the upper end of the pipe and the top wall of the cap. 75

2. In a refrigerator drain, the combination of a bowl, a drain pipe extending upwardly through the bottom of the bowl, a cap having an annular flange extending downwardly in the bowl around and spaced from the upper end of the pipe, a collar secured to the upper end of the pipe and having a lateral hinge lug and the cap having a lateral extension embracing the lug and hinged thereto, said collar being provided with a plurality of lugs extending upwardly at intervals therearound, so as to hold the top wall of the cap at an elevation above the upper end of the pipe. 95

3. In a refrigerator drain, the combination of a bowl, a drain pipe extending upwardly through the bottom of the bowl, a collar threaded on the upper end of the pipe spaced from the bowl bottom, a cap having an annular flange extending downwardly in the bowl around and spaced from the upper end of the pipe and laterally from the pipe and collar, a hinge pivotally connecting the collar and cap so that the latter is adapted to be swung away from the upper end of the pipe, and a plurality of upwardly extending lugs on the collar arranged at intervals therearound outwardly of the pipe for holding the top wall of the cap at an elevation above the upper edge of the pipe. 110 105 115

4. In a refrigerator drain, the combination of a bowl, a drain pipe extending upwardly through the bottom of the bowl and having a collar secured on each end thereof, a cap hinged on the upper collar and having an annular flange extending downwardly in the bowl around and spaced from the upper end of the pipe, means on the upper collar for holding the top wall of the cap at an elevation above the upper end of the pipe, and a spout suspended from the collar on the lower end of the pipe. 120 125

5. In a refrigerator drain, the combination with a lining, of a bowl seated in a depression below the lining, the bowl having 130

an opening in the bottom with an upturned flange, a drain pipe extending up through the opening and anchored to the flange to form a liquid seal therebetween, said pipe extending considerably above the flange, a cap having a surrounding depending flange extending below the upper end of the pipe, a collar detachably mounted on the upper end of the pipe above and spaced from the flange and having means to support the cap ¹⁰ in spaced relation to the upper end of the pipe with openings affording a circulation space and water seal under the cap between the pipe and bowl.

LOTHAR von DABROWSKI.
